UNITED STATES PATENT OFFICE

152,764

DESIGN FOR A COMBINED GRATER AND
RECEPTACLE

Charlie J. Bassett, Fairfax, Ala.

Application January 27, 1948, Serial No. 144,067

Term of patent 3½ years

(Cl. D89—1)

To all whom it may concern:

Be it known that I, Charlie J. Bassett, a citizen of the United States, residing at Fairfax, in the county of Chambers and State of Alabama, have invented a new, original, and ornamental Design for a Combined Grater and Receptacle, of which the following is a specification, reference being had to the accompanying drawing, forming part thereof.

Figure 1 is a front perspective view of a combined grater and receptacle, showing my new design, and

Figure 2 is a rear perspective view thereof.

I claim:

The ornamental design for a combined grater and receptacle, as shown.

CHARLIE J. BASSETT.
